UNITED STATES PATENT OFFICE.

NATHAN J. GOLDFARB, OF NEW YORK, N. Y., ASSIGNOR OF ONE-HALF TO ABRAHAM DRUSIN,
OF BROOKLYN, NEW YORK.

ADDING-MACHINE.

No. 921,539.

Specification of Letters Patent.

Patented May 11, 1909.

Application filed May 18, 1908. Serial No. 433,368.

To all whom it may concern:

Be it known that I, NATHAN J. GOLDFARB, a citizen of the United States, residing at New York, in the borough of Brooklyn, county of Kings, and State of New York, have invented certain new and useful Improvements in Adding-Machines, of which the following is a specification.

This invention relates to adding machines, 10 and more particularly to the type of machines described in Letters Patent No. 844,120 granted me under date of February 12, 1907.

The invention aims to improve the general construction of the machine described in this 15 patent, and particularly the carrying mechanism.

A further object of the invention is to provide a machine having an itemizing attachment by means of which certain columns 20 may be used to automatically register the number of items added in the other columns. This itemizing device is so arranged that upon every actuation of the carrier-energizing bar, which precedes every addition, the 25 numeral-carrying elements of certain columns will be actuated by this bar, so that the total number of items added by the machine will appear with the result of the addition.

The invention also aims to provide a checking device for the chains employed, by which the latter are prevented from running too far when actuated. This device serves to lock the chains after each actuation, and therefore also serves as a reminder that the carrier-energizing bar must be actuated, said device being releasable only upon the actuation of this bar.

A still further object of the invention is to provide an automatic connection between 40 the carrier-energizing bar and the zero-setting device whereby, when the numeral-carrying elements are set to zero, the carriers will at the same time be automatically released by the checking or locking mechanism, 45 and so connected with the zero-setting device as to be energized and carry the elements to zero. Thus the carrying mechanism aids the zero-setting mechanism and causes all of the numeral carrying elements 50 to be simultaneously moved to zero position.

This additional function of the carriers also serves to cause all the elements to be properly and uniformly set to zero, which would not otherwise be the case if certain of the carriers were released at the end of the addi- 55

tion. Without this connection of the zero-setting mechanism with the carrying mechanism, by which all the carriers are energized and actuated at the proper time, the carriers which remain energized would carry those 60 which are not energized from 0 to 1 when setting to zero.

The invention also contemplates the provision of a zero-setting device which acts on the chain-wheels which are at the front of the 65 machine, so that the chains pull the chain-wheels at the rear of the machine, which carry the numbers, into position, instead of pushing the same as is usual in machines of this type. This change in the construction 70 results in the easier setting of the number-wheels to zero.

With these ends in view the invention consists in the novel features and combinations of parts to be hereinafter described and 75 claimed.

In the accompanying drawings, in which the same reference characters denote the same parts throughout the views, Figure 1 is a perspective view of an adding machine 80 constructed according to the invention, Fig. 2 is a section on line 2, 2, Fig. 1, Fig. 2^a is a similar view, but is drawn on a larger scale and shows the parts in a different position, Fig. 3 is a top view of the adding mechanism 85 removed from the casing, Fig. 4 is a bottom view of Fig. 3, Fig. 5 is an end view of the right-hand end of the machine with the side-plate removed, Fig. 5^a is a detail of part of Fig. 5, but showing another position of the 90 carrier-energizing mechanism, Fig. 6 is a view of the left-hand end of the machine with the corresponding side-plate removed, Fig. 6^a is a detail transverse section showing part of the zero-setting mechanism, Fig. 7 is 95 a rear view of the adding mechanism with the rear-plate of the casing removed, Fig. 8 is a detail perspective view of one of the carriers and its corresponding trigger, and Figs. 9 and 10 are detail transverse sections 100 of the machine showing a modified form of the carrying mechanism in which two triggers are used in connection with each carrier, for a purpose which will hereinafter appear.

In its main features the present machine is constructed on the lines of my patented machine heretofore mentioned. It comprises a casing 10 having an inclined front-face provided at its upper part with the 110

usual apertures over the number-wheels. It also has a number of parallel slots in which the chains 11 move over a glass cover under which the numbers are arranged on a suitable card, as shown in Figs. 1 and 2.

The chains 11 run on wheels 12 and 13, of which the latter carry numbers which show through the apertures in the face of the casing at the upper rear part thereof, while the 10 chain-wheels 12 are entirely hidden from view in the lower front part of the casing. Each chain with its two wheels is arranged in a transverse compartment of the casing. These transverse compartments are formed 15 by means of partitions through which the shafts 14 and 15 of the chain-wheels pass.

The carrying mechanism is located beneath the chains and adjacent the number-wheels 13. Each number-wheel carries at 20 one side a pin 16 which coacts with one arm of a trigger 17. One trigger is mounted in each compartment on a shaft 18 which extends through the partitions, being pivoted to swing on said shaft and acted upon by a 25 small spring 19 holding it in position after engaging with the corresponding pin 16 on the number-wheel. The said trigger is preferably stirrup-shaped, as shown in Fig. 8, and is disposed in two compartments, so 30 that when its arm is engaged by the pin 16 the trigger will release the carrier in the adjacent compartment.

The carriers 20 are of substantially U-shape and pivoted on a shaft 21 extending 35 parallel to the trigger-shaft 18. Springs 22 coiled about the shaft 21 normally press the carriers in upward direction toward the chains 11. At the upper part of each carrier there is pivoted a spring-actuated dog 40 23 having a projection 24 which enters the links of the corresponding chain, so that when the carrier is moved upwardly the chain will be actuated and move its number-wheel to the extent of one unit. The triggers 17 coact with the carriers 20 by means 45 of extensions 25, one of which is carried by each trigger. Each such extension has a notched end 26 coacting with a shoulder 27 formed at one side of the carrier in the leg 50 thereof, as shown in Fig. 8. In this manner the carrier may be held in its lowermost position, as shown in Fig. 2, until the pin 16 of the number-wheel in the adjacent compartment strikes the trigger, whereupon the extension 25 of the latter in being moved upwardly releases the carrier, as shown in Fig. 55 2^a, and permits the latter under the influence of its spring 22 to actuate the chain and number-wheel.

60 At the points where the pivoted dogs of the carriers engage the lower runs of the chains, the latter are guided over a plate 28 extending longitudinally of the machine through the bights of the chains and the transverse 65 partitions. As said plate is at the side of the

chain opposite the dogs so that the chain runs between the plate and dog, the proper engagement of the latter with the chain is insured.

For the purpose of energizing or setting the carriers, a carrier-setting bar 29 is employed. Said bar extends longitudinally of the machine and is moveable in forward and rearward direction in slots 30 cut in the partitions. When the bar is moved forwardly 70 against the action of springs 29^x it will press down the carriers from the position shown in Fig. 2^a to that shown in Fig. 2 so that the triggers will again engage the carriers and hold them set, ready for another actuation of 75 the machine.

At its ends which project beyond the end partitions within the casing, the bar 29 is connected by means of connecting rods 31 with levers 32 pivoted on a shaft 33 extending through the partitions. The levers 32 operate in slots 34 at the lower front part of the casing and are connected by a bar 35 extending across the front of the machine. It is obvious that when this bar is depressed the carrier-setting bar 29 will be moved forward, by the connections described, in order to set the carriers. When the operating bar is released, the parts are returned by the springs 29^x. A ratchet mechanism 36, 37 is arranged in connection with one of the levers 32 in order to insure a complete depression of the operating bar 35.

In order to prevent the overrunning of the chains, the following mechanism is employed: Each chain travels over a roller 38 located in the bight of the chain and coacting with a small roller 39 which is mounted on a pivoted arm 40 acted on by a spring 41 in such a manner that the roller 39 is pressed into the links of the chain against the larger supporting roller 38. The carrier 20 in the same compartment is provided with a tongue 20^x, which after the carrier has been released by the corresponding trigger presses on the roller 39, as shown in Fig. 2^a, so that said roller is frictionally held against the chain and causes the same to come to a stop at the proper point. This frictional locking device may be used alone or in conjunction with a positive locking device, two devices for this purpose being provided so that if one gets out of order the locking will still be effected by means of the other. The positive locking device is formed by a projection 25^x 110 extending upwardly from the extension 25 of the trigger. When the latter is thrown upwardly and released from the carrier said projection 25^x will take into one of the chain-links and abut against the guide-plate 28, as shown in Fig. 2^a, whereby the further movement of the chain is positively prevented. These locking devices also serve as a reminder that the carrier-setting bar 115 must again be actuated before another actu- 120

- ation of the machine. When it is seen that the chains are locked the carrier-setting bar is actuated and this causes the release of both locking devices. As each carrier is re-
5 turned to set position, as shown in Fig. 2, its tongue 20^x will be moved away from the locking roller 39, and the trigger 17 in being moved into set position will release its projection 25^x from the chain.
- 10 The number-wheels are set to zero after each addition by means of the following mechanism: The shaft 14 of the lower front chain-wheels 12 carries adjacent each such wheel a cam 42 fixed to said shaft and pro-
15 vided with a notch in which a pawl 43 pivoted on the face of said wheel engages, as shown in Fig. 6^a. The pawl 43 is pressed into engagement with said notch by means of a spring 44 also mounted on the wheel.
- 20 At one side of the machine said shaft 14 is connected by means of a train of gears 45, 46, 47, 48 mounted on the end-partition with a shaft 49 extending through the partitions at the upper part of the machine and 25 carrying at one end a hand-crank 50, as shown in Figs. 1 and 6.

By rotating the shaft 49 by means of said hand-crank the shaft 14 is rotated (through the train of gears) so that its cams 42 make 30 a full revolution and by engaging the pawls 43, which are located in various positions due to the varying positions of the number-wheels, cause the chain-wheels 12 to be moved into such position as to pull the 35 number-wheels 13, by means of the chains 11, into their initial or zero position. The gear 45 carries a pin 45^x against which a spring 45^y presses in such a manner as to form a stop for the shaft 14 and insure its 40 being arrested in the proper position. The shaft is moved slightly beyond the zero position against the action of said spring and when released the latter will move the shaft in the opposite direction to a slight 45 extent.

When the shaft 14 is moved in such a manner as to move the chain-wheels to zero the pawls 43 engage the notches in the cams 42 until the chain-wheels are all carried along to 50 zero position. When the shaft is released it will move backwardly to such an extent that the notches of the cams will be moved away to a slight extent from the pawls 43. In this manner, when the chains are used for 55 adding, the pawls in riding around the cams will be sure to pass over and into the notches of the cams so that proper engagement is produced for the setting of the adding elements to zero.

60 The fact that the number-wheels are pulled into zero position, instead of being pushed as is customary, is of considerable importance, as the crowding of the chains is dispensed with and the easier operation of 65 the machine produced.

The gear 48 carries a pin 51 which fits into a slot 52 formed in one end of a connecting rod 53 secured at its other end to the lever 32 at the same side of the machine. The said connecting rod forms an automatic connection between the carrier-setting mechanism and the zero-setting mechanism by which when the number-wheels are set to zero the carrier-setting mechanism is operated.

75 It is apparent that before the machine can be set to zero the locking devices hereinbefore described will have to be released from the chains, and this necessitates a depression of the operating bar 35 of the carrier-setting mechanism. This is produced by means of the connection between the connecting rod 53 and the gear 48. As the zero-setting mechanism must remain inoperative until after the depression of the operating bar 35, the gear 48 is mutilated, 80 having a number of teeth cut away at 48^x, and this cutaway part is engaged by a tooth 47^x on the gear 47. Thus the movement of the gear 48 which is transmitted by means 85 of the connecting rod 53 to the lever 32, is not transmitted to the gears 47, 46, 45 and shaft 14 until the lever 32 has been depressed and the tooth 47^x arrives at the end of the cutaway portion 48^x of the gear 48. As 90 soon as the teeth of the gears 47, 48 engage each other in the ordinary way the shaft 14 will be rotated and the number-wheels thereby set to zero, as before indicated.

95 The action of the stop 45^x and spring 45^y 100 with respect to the shaft 14 is aided by the connection of the zero-setting mechanism with the carrier-setting bar 29. It is obvious that the levers 32 are normally pulled in upward position by the springs of this 105 carrier-setting bar, and the connection between one of the levers 32 and gear 48 is made in such a way that after the release of the hand-crank 50 the said lever 32 will be moved upwardly to a certain extent under 110 the influence of the spring-actuated carrier-setting bar, so that through the train of gears the shaft 14 will be moved backwardly to a slight extent. Thus the notches of the 115 cams are moved slightly away from the pawls, as before indicated.

120 The connection between the zero-setting device and the carrier-setting bar causes the carrying mechanism to be coupled with the zero-setting mechanism in such a manner as to aid in the operation of the latter. Through the connections described, when the zero-setting hand-crank 50 is operated, the levers 32 are depressed, whereby the carrier-setting bar 29 is pulled down and sets the carriers and then the bar is moved back to its initial position. The release of the chains is effected in the manner described and by the operation of the shaft 14 the chain-wheels are carried along from their various positions until 130

the number-wheels all reach the number 9, whereupon, upon a further actuation of the hand-crank 50, the pins on the number-wheels will engage their respective triggers, causing all the number-wheels to be carried to 0 instead of being pulled into this position from 9.

In adding machines of this type, when certain of the carriers remain energized at the 10 end of the adding operation, these carriers usually act upon their number-wheels, when the machine is set to zero, in such a manner that the latter will be carried from 0 to 1, so that while 0 appears through certain apertures in the casing, 1 appears through other of such apertures. By the connection with the carrying mechanism hereinbefore described this is obviated, as all the carriers are energized at the same time automatically by 20 the operation of the zero-setting hand-crank and then released to permit the carrying of the number-wheels to their zero-position. Thus the uniform movement of all the number-wheels to zero is produced.

25 One or more of the columns at the left-hand side of the machine may be utilized for the addition of the items added by the columns on the right. To this end an itemizing device is provided which is automatically 30 operated by the carrier-setting mechanism so that when this mechanism is operated, which is necessary after every addition of an item, the number-wheels at the left of the machine will be so actuated as to register 35 the number of items so added. This is caused by means of keys 54, of which one is used for each column utilized for adding items, these keys, of which two are shown, being mounted in the casing directly above 40 the itemizing columns. Each key 54 has a curved lower end 55 engaging with the corresponding trigger 17 at the intermediate part of the latter, and by depressing said key 45 said trigger may be moved slightly, but to such an extent that its notched end 26 will be moved out of engagement with the shoulder 27 of the corresponding carrier. Thus when the carrier-setting bar is actuated the carrier is moved forward as usual, but as it 50 will not engage with the trigger it will spring back under the influence of its spring and thereby push the chain forward to the extent of one unit. Hence the registering of the items added is automatically produced 55 by the carrier-setting mechanism.

In the machine illustrated two columns at the left of the machine are used for itemizing purposes. The two depressible keys 54 are connected beneath the cover-plate of the casing by means of a pivoted lever 56 in such a manner that only one of the itemizing columns may be used at a time, one key being in its uppermost position while the other is depressed. The lever 56 is held in position 60 by means of a catch 57.

It sometimes happens that when the chains are pulled down to move the number-wheels to 9 the shock will be great enough to cause the chains and their wheels to overrun, thus producing the abutment of the pins 16 70 with their triggers and causing the carrying of the number-wheels to zero. At first glance it might appear that this could be overcome by moving the pins 16 back on their wheels to a certain extent. But when 75 this is done and the carrying takes place at the last possible moment, the triggers remain in contact with the pins after the carrying operation and are thus held with their extensions in raised position, out of the path 80 of the carriers, so that the carriers cannot be set again by the carrier-setting bar 29.

The difficulty referred to has been solved by providing the construction illustrated in Figs. 9 and 10. Instead of using one trigger, 85 two triggers are employed in connection with each carrier, said triggers having a common pivot and being located one within the other on the same shaft. Each number-wheel is provided with the usual pin 16, which first 90 coacts with the inner spring-actuated trigger 58 and then with a second outer spring-actuated trigger 59. The extension 60 of the inner trigger 58 is provided with a shoulder which engages with the carrier in substantially the same manner described in connection with Fig. 8, and the outer trigger 59 has a similar extension 61 having a similar shoulder, which, however, is held behind the shoulder of the trigger 58 in such a manner 95 that the latter shoulder will first engage the carrier, the shoulder of the other trigger being 100 out of engagement therewith.

The upwardly extending arm of the trigger 58, which strikes the pin 16, is of the usual 105 form, but the upwardly extending arm of the outer trigger 59 is made hook-shaped, as shown, so that when the pin strikes and actuates said trigger it will remain in contact with the end of the same, as shown in Fig. 10.

110 The operation of this mechanism is as follows: The pin 16 first strikes the inner trigger 58, and as this trigger is entirely independent of the trigger 59 it will be moved to a certain extent, independent of said trigger 59, into such position that its shoulder will release the carrier, whereupon the carrier will move upwardly to a slight extent until it engages with the shouldered extension 61 of the trigger 59. This position of the parts is 115 shown in dotted lines in Fig. 9. Upon a further movement of the number-wheel and its pin the latter will engage the upwardly extending hooked end of the trigger 59 and said trigger will be rocked into the position 120 shown in Fig. 10, thus releasing the carrier and permitting it to advance the chain and corresponding number-wheel.

125 It is understood that the pin 16, which is merely indicated in dotted lines, is carried 130

by a number-wheel located in advance of the one illustrated in Figs. 9 and 10.

As before indicated, when the carrying operation has taken place the parts assume the position shown in Fig. 10, in which the hooked arm of the trigger 59 is still in engagement with the pin 16. It is apparent that while in this position the trigger 59 cannot be engaged with the carrier when the carrier-setting bar is pulled against the latter to set the same. However, the carrier is set by means of the trigger 58, which is in position to properly engage the carrier, said trigger being independent in its movement of the trigger 59. Hence the inner trigger acts as a setting trigger, while the outer trigger acts as a releasing trigger to release the carrier at the very last moment, so that premature carrying will not take place. Upon a further movement of the number-wheel the pin 16 will move beyond the trigger 59, whereupon the parts will again take the position shown in Fig. 9.

Having thus described my invention, I claim as new and desire to secure by Letters Patent:

1. In an adding machine, the combination, with chain-wheels, an endless chain connecting the same, of a plate within the bight 30 of the chain over which the chain is guided at its lower run, and a pivoted spring-actuated carrier beneath such run of the chain which takes into the links of the chain where the latter is supported by said plate, a pivoted trigger controlling the carrier, and trigger-operating means.

2. In an adding machine, the combination, with chain-wheels and a chain running thereon, of a plate over which the chain is guided, a pivoted spring-actuated carrier, means to operate said carrier, and a pivoted dog mounted on the carrier to take into the links of the chain where the latter is supported by said plate.

45 3. In an adding machine, the combination, with chain-wheels and a chain, of a plate over which the chain is guided, a pivoted carrier, a spring-actuated dog pivoted on the carrier at the free end thereof and having a projection to take into the links of the chain where it is supported by said plate, and carrier-operating means.

4. In an adding machine, the combination, with chain-wheels and a chain thereon, of a pivoted spring-actuated carrier of U-shape having a shoulder formed at the side thereof in one of the legs, a trigger having a notched end coöperating with said shoulder, and trigger-actuating mechanism.

60 5. In an adding-machine, the combination, with a number-wheel, and a chain to operate the same, of a carrier to advance the chain, and a setting trigger for the carrier which takes into the links of the chain after each

carrying operation and positively locks the same against further advance.

6. In an adding machine, the combination, with a number-wheel and a chain to operate the same, of a spring-actuated carrier to advance the chain, and means operated by the carrier to engage and directly lock the chain after each advance of the same by the carrier.

7. In an adding machine, the combination, with an operating chain, of a carrier, and means operated by the carrier to grip and frictionally lock the chain.

8. In an adding machine, the combination, with an operating chain, of a carrier to advance the chain, and members between which the chain is frictionally gripped automatically after each carrying operation.

9. In an adding machine, the combination, with a number-wheel and an operating chain, of a supporting roller for the chain, a locking roller, and a carrier to advance the chain and press said locking roller against the latter and said supporting roller.

10. The combination, with an adding element comprising a chain, of a supporting roller for said chain, a pivoted locking roller coacting with said supporting roller and between which and the latter the chain passes, and a carrier which when operated to advance the chain presses the locking roller against the latter and said supporting roller.

11. The combination, with an adding element comprising a chain, of rollers between which said chain passes, one of said rollers being movably mounted, and a carrier having a tongue coacting with said movably mounted roller.

12. The combination, with an adding element comprising a chain, of a spring-actuated carrier, and a trigger to hold the carrier in set position and positively lock the chain after the release of the carrier.

13. The combination, with an adding element comprising a chain, of a spring-actuated carrier, a trigger by which the carrier is held in set position and which has a projection to enter the links of the chain and stop the same upon the release of the carrier, and trigger-operating means.

14. In an adding machine, the combination, with a carrier-setting bar and zero-setting mechanism, of a connection between said bar and said mechanism by which the former is operated by the latter.

15. In an adding machine, the combination, with the adding elements and carrying mechanism therefor, of zero-setting mechanism, and a connection between said zero-setting mechanism and said carrying mechanism by which the latter is operated to move the adding elements to zero.

16. In an adding machine, the combina-

- tion of a plurality of adding elements comprising chains and number-wheels, spring-actuated carrying mechanism, means to pull the chains and number-wheels to zero, and a connection between said means and said carrying mechanism by which the latter is energized and operated to move the number-wheels from 9 to 0. 65
17. In an adding machine, the combination of chain-wheels at the front and rear of the machine, the wheels at the rear of the machine being number-wheels, chains connecting the front and rear wheels, a shaft upon which the front wheels are mounted, and means in connection with said shaft by which the number-wheels are pulled by the chains into zero position. 70
18. The combination, with the front chain-wheels, of a shaft upon which the same are mounted, means in connection with said shaft to carry the wheels to zero position, a second shaft extending parallel to the first-named shaft and carrying a hand-crank, and a train of gears connecting said shafts at one side of the machine. 75
19. The combination, with adding elements comprising chains, of carrying mechanism for the chains, locking mechanism for the chains operated by said carrying mechanism, a carrier-setting bar, zero-setting mechanism, and a connection between said bar and said zero-setting mechanism by which before the latter is operated the locking mechanism is released. 80
20. In an adding machine, the combination of a plurality of adding elements arranged in columns, and devices in connection with certain of said elements by which the number of items added by the other elements is automatically registered by said first-named elements. 85
21. In an adding machine, the combination of a plurality of adding elements comprising chains, and devices in connection with certain of said elements by which the number of actuations of other elements is automatically registered. 90
22. In an adding machine, the combination, with number-wheels, and operating chains, of carrying-mechanism for the chains, means to set the carrying-mechanism, and means in connection with certain of said chains by which they are advanced by the carrier-setting mechanism. 95
23. In an adding machine, the combination, with adding elements, of carrying-mechanism, means to set the carrying-mechanism, and itemizing-mechanism operated by said setting mechanism. 100
24. In an adding machine, the combination of adding elements comprising chains, spring-actuated carriers coacting with said chains, triggers controlling the carriers, a carrier-setting device, and means in connection with one of said elements by which the corresponding trigger is held out of co-operative relation with its carrier, whereby the operation of the carrier-setting device will automatically advance said chain. 105
25. In an adding machine, the combination of an adding element comprising a chain, a spring-actuated carrier to advance the chain, a trigger coacting with the carrier, a carrier-setting device, and means by which the trigger is held out of co-operative relation with the carrier. 110
26. In an adding machine, the combination of an adding element comprising a chain, a spring-actuated carrier to advance the chain, a trigger coacting with the carrier, a carrier-setting device, and a key by which the trigger is held out of co-operative relation with the carrier. 115
27. In an adding machine, the combination, with adding elements comprising chains, of spring-actuated carriers, triggers coacting therewith, a carrier-setting device, keys to hold the certain triggers out of the path of their carriers, and a connection between the keys by which only one may be operated at a time. 120
28. In an adding machine, the combination of chains and chain-wheels, a shaft on which said wheels are mounted, cams on said shaft having notches, pawls on the wheels to engage in said notches of the cams, and zero-setting mechanism comprising means to move the shaft backwardly to a slight extent after the movement of the chain-wheels to zero position, whereby the notches of the cams are moved away slightly from the pawls. 125
29. In an adding machine, the combination, with number-wheels and chains running thereon, of spring-actuated carriers for the chains, a setting and a releasing trigger in connection with each carrier, and a pin on each number-wheel by which the triggers are successively released from the corresponding carrier. 130
30. In an adding machine, the combination of an adding element comprising a chain, a spring-actuated carrier to advance the same, a setting trigger, a releasing trigger, and trigger-actuating mechanism. 135
31. In an adding machine, the combination of an adding element comprising a chain, a carrier to advance the same, a trigger to hold the carrier set, a releasing trigger, means to successively activate the triggers, and means to return the carrier to set position to engage the setting trigger. 140
32. In an adding machine, the combination of adding elements comprising chains and adjacent number-wheels, a pin carried by one of said number-wheels, carrying mechanism for the other chain comprising a spring-actuated carrier, a trigger for said carrier 145

which is first released by said pin but which does not release the carrier, and a releasing trigger which is engaged by said pin on its further movement and released from the carrier, said releasing trigger remaining in contact with the pin after the carrying operation.

33. In an adding machine, the combination of an adding element comprising a chain, 5 a spring-actuated carrier to advance the same, a trigger for releasing the carrier,

means for actuating said trigger, a carrier-energizing bar, and a trigger by which the carrier is set and which is released in advance of said first-named trigger.

In testimony, that I claim the foregoing as my invention, I have signed my name in presence of two subscribing witnesses.

NATHAN J. GOLDFARB.
